OPERATING MECHANISM FOR OSCILLATING GRATES

Cyrenius Losch, Schuylkill Haven, Pa.

Original application February 4, 1929, Serial No. 337,211. Divided and this application January 30, 1930. Serial No. 424,489

3 Claims. (Cl. 126—169)

My invention relates to new and useful improvements in operating mechanism for oscillating grates, being a division from my co-pending application, Serial No. 337,211, filed February 4, 1929, and has for one of its objects to provide mechanism of this kind which is simple in construction, inexpensive in the cost of manufacture, reliable in action and requires little or no attention during operation.

10 Another object of the invention is the provision of an effective mechanism for intermittently oscillating a grate.

A further object of the invention is to construct a unique mechanism for regulating the stroke to control the amount of fuel fed to a grate.

The invention will be best understood from a consideration of the following detailed description, taken in connection with the accompanying drawings forming a part of this specification, with the understanding, however, that the embodiment illustrated, though practical, is by no means the only embodiment which the invention may assume, wherefore the invention is not confined to any strict conformity with the showing in the drawings, but may be changed and modified in various particulars, so long as such changes and modifications mark no material departure from the salient features of the invention.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1 is a plan view of a furnace grate and operating mechanism constructed in accordance with my invention, the furnace walls being shown in section along a line 1—1 of Fig. 2.

45 Fig. 2 is a section on the line 2—2 of Fig. 1, with the operating mechanism in elevation.

Fig. 3 is a section on the line 3—3 of Fig. 2.

Fig. 4 is a section on the line 4—4 of Fig. 1.

50 Fig. 5 is an enlarged side elevation of the cam.

Fig. 6 is an edge view thereof looking toward the bottom of Fig. 5.

Fig. 7 is an enlarged side elevation of the pivoted, swinging link and connecting rod, a portion of the link being broken away and shown in section to illustrate a detail of construction.

Fig. 8 is an enlarged top plan or edge view of the ratchet mechanism, the arms of the pawl controls being broken away and sectioned to show the formation of a hole, whereby an operating means may be connected with said controls.

Fig. 9 is a side elevation or face view thereof with a connecting rod attached to the rocker arm.

Fig. 10 is a rear edge view of the same or looking toward the right hand edge of Fig. 9.

In carrying out my invention as herein embodied, 15 represents the grate which is of general rectangular shape and includes the bottom 16 consisting of parallel spaced inner and outer walls 17 and 18 respectively, sides 19 and a front 20, said sides also consisting of inner walls 21 and outer walls 22 while the front consists of an inner wall 23 and an outer wall 24, all considered together forming a hollow grate, the interior of which acts as a water compartment 25.

In the outer walls of the sides adjacent the bottom as well as adjacent the upper end of the grate front 20 are formed suitable openings to receive pipes 26, 27, 28 and 29. The pipe 26 acts as an inlet and may be connected by means of a flexible conduit 30, such as a rubber hose, with a source of water supply while the pipe 27 which acts as an outlet is connected by a flexible conduit 31, such as a rubber hose, with a point of disposal, such as a sewer or a hot water reservoir or the water tubes of a boiler.

The pipes 26 and 27 in connection with the other pipes 28 and 29, the latter being closed by stoppers 32, such as plugs, act as mountings for the grate and pass through apertures 33 in the side walls of the furnace 34, said apertures being of sufficient size to permit movement of the pipes which act as trunnions.

As plainly shown in Fig. 2, the grate is inclined from the rear toward the forward end so that as the water becomes heated, it will readily circulate toward the outlet and as will be obvious from the succeeding description, the fuel, the fire bed, and the ashes will be readily moved toward the rear end of the grate.

The pipes 26 to 29 inclusive each rests between a pair of shoes 35, 36 held in place by springs 37 and 38, the outer ends of which engage brackets 39, 40 mounted on the side of the furnace so that in fact, the lower springs actually support the grate and any fuel thereon and will flex sufficiently to permit of the oscillation of the grate with little or no noise. Any other means for supporting the grate at the ends thereof may

be substituted for the springs and associated parts.

The apertures through which the several pipes or trunnions pass are closed by closure sheets 41 which may be of asbestos held in place by suitable holding means 42, which for convenience of illustration, are shown as rings forced upon the pipes.

Within the water compartment of the bottom 10 of the grate are located a plurality of suitably spaced columns 43 which extend from a point adjacent to the rear of the grate to another point short of the front of the grate as shown in Fig. 1 and said columns can be cast with the grate and 15 are hollow so as to form air passageways 44 therethrough from the underside or outside of the outer wall of the grate bottom and the openings through the bottom or outer wall are the same diameters as the bores through the column, but 20 the openings through the inner or top wall are preferably reduced in size and are preferably of conical shape so as to form the air nozzles 45.

The lower ends of the air passageways 44 communicate with an air distributing chamber 46 located on the bottom or underside of the grate and while this chamber may be produced in any well known or desired fashion I preferably secure a flange-like frame 47 to the bottom wall of the grate, which frame is of sufficient size to surround or enclose all of the air passageways and the lower open portion of the frame is then closed by a plate 48 which is provided with a depression 49 at its rear and preferably transversely thereof. It is desirable that said depression, which is like 30 a gutter or channel, run all the way across the air distributing chamber so that as the air enters, it will be guided to all parts of the chamber and practically equalize the air pressure. The depression has an inlet 50 leading thereto preferably at one side, which inlet is defined by a short length of pipe 51 projecting through an opening similar to the ones above described and designated by the numeral 33 and also closed in a similar manner.

45 Air is preferably forced to and caused to enter the distributing chamber by means of a fan or blower 52, the outlet of which may be connected by a flexible conduit 63 with the pipe 51 and for convenience of illustration, said fan or blower is shown as being operated from a source of power 54, such as an electric motor through the medium of a belt 55 and coacting pulleys.

The following description relates particularly to subject matter of the invention embodied in 55 this application. To some suitable support, preferably the front wall of the furnace, is secured a bracket 56 and on this are mounted two pedestals 57 and 58 which are provided with bearings 59 and 60 respectively to journal the operating shaft 61. This operating shaft carries a ratchet wheel 62 and a jump cam 63, both of which are secured to said shaft so as to partake of the same rotative movement.

In order to transmit motion to the operating 65 shaft 61, I have shown what, for convenience, I term a power shaft 64 journaled in suitable pedestals 65 and receiving motion from the motor 54 through a belt 66 and co-operating pulleys. On the power shaft 64 is an eccentric 67, or its equivalent, to which is pivoted one end of a rod 68, the opposite end of said rod being pivoted to a rock-arm 69 which is journaled upon the operating shaft 61 so as to swing freely thereabout through a certain arc due to the motion transmitted from the eccentric.

It is preferable that the rod 68 be connected with the lower end of the rock-arm 69 while to the upper end is pivoted a pawl 70 adapted to engage and drive the ratchet wheel 62 in one direction equal to the full swing of the rock-arm, 80 or any portion thereof, as will be hereinafter more fully explained.

Any movement thus imparted to the ratchet wheel 62 will rotate the operating shaft 61 and advance the rotation of the jump cam 63 a similar amount or distance. The jump cam 63 contacts with the free end of a swinging link 71 which is pivoted at its upper end as indicated at 72 to the pedestal 57 and has a notch 73 formed in the edge thereof adjacent the cam so as to receive the high part of said cam at certain times and under certain conditions, said swinging link also has a tapered hole 74 therethrough for the reception of the adjustable pull bolt 75, one end of which is connected with the grate while on the end passing through the swinging link are threaded suitable nuts 76 and 77, the latter preferably having a convex portion to set in the cavity 78 in the edge of the swinging link at the smaller end of the hole 74.

Push rods 79 are also fastened to the grate and pass through the front wall of the furnace or heating device and project through the upstanding wall 80 of the bracket 56 and about said rods are coiled impulse springs 81, one end of each 105 engaging the inner surface of the upstanding wall 80 and the other end engaging means 82 adjustable on each rod, such means here shown as washers and nuts, the latter having threaded engagement with the rods. Also coiled about 110 said rods on the opposite side of the upstanding wall 80 are cushion springs 83, one end of each engaging the outer surface of the upstanding wall 80, while the other end engages a cushion plate 84 through which the push rods pass and 115 said plate is held in certain adjusted positions relative to the upstanding wall 80 by means of bolts 85 passing through the cushion plate and having threaded engagement with the upstanding wall 80 of the bracket 56.

On the outer ends of the push rods which project through the cushion plate are mounted stops 86 preferably of rubber, so as to serve as silencers and these stops are adjustable lengthwise of the push rods by means of suitable nuts 87.

The operating shaft 61 being advanced or rotated through the medium of the ratchet wheel 62 as hereinbefore mentioned, the cam 63 engaging the swinging link 71 will pull the grate forward by small increments through the medium 130 of the pull bolt 75 and this action moves the push rods 79 outward since they are attached to the grate, thereby compressing or increasing the compression of the impulse springs 81.

I say that the compression is increased because I prefer that both impulse and cushion springs be under compression at all times.

As soon as the high point of the cam 63 registers with the notch 73 in the swinging link 71, the grate is free to move in the opposite direction and since the impulse springs 81 are under compression, they will immediately act to force the grate rearward through the medium of the push rods 79. This movement is very quick, but will be suddenly arrested when the stops 86 engage the cushion plate 84, but the shock due to the contact of the stops with the cushion plate will be absorbed by the cushion springs 83. The quick horizontal rearward movement of the grate and this sudden arrest causes the fuel and 150

ashes thereon to shift or move toward the lower rear end of the grate where a small portion of the ashes are discharged during each movement of the grate into a receptacle or other device for proper disposal thereof as desired. The means for disposing of the ashes not being a part of the invention have not been illustrated, but for a thorough understanding of the invention, it might be well to state that an elevator or conveyer could be so disposed that the rear of the grate has to receive the ashes and convey them to a point of disposal.

The frequency of the grate movements are taken care of by the ratchet wheel arrangement above referred to, particularly in connection with a pair of rings 88 and 89, the rings of said pair being disposed on opposite sides of the ratchet wheel, preferably on hubs 90 formed with the ratchet wheel. These rings each have a portion 20 of their periphery raised as indicated at 91 so that when occupying a certain position, they will engage ears 92 on the pawl at opposite sides of its nose 93 and hold the nose of said pawl from engagement with the ratchet wheel 62 during 25 a portion of the advancing movement of said pawl. In other words, the pawl can be held out of engagement with the ratchet during any desired portion of the movement of said pawl. For instance, said pawl may engage the ratchet 30 wheel after said pawl has moved one-sixth of its complete travel or the rings 88 and 89 may be so adjusted by moving them clockwise that the pawl will not engage the ratchet wheel until after it has moved three-fourths of its traveling 35 distance. In one case, the ratchet wheel might be moved a distance equal to four teeth and in the other case, it might be moved a distance equal to one tooth. The rings 88 and 89 are each provided with an arm 94 which are fastened together 40 by suitable fastening devices 95 and in the ends of these arms are formed coinciding notches, which when the arms are brought together produce a hole 96 for the reception of any suitable actuating member or element so that the rings 45 may be moved either manually or thermostatically, to either decrease or increase the time of actual engagement of the pawl with the ratchet wheel, thus securing a wide range of idle movement and active engagement for varying the 50 movement of the cam 63 and consequently the number of impulses imparted to the grate in a specified time for the purpose of shifting the fuel, fire bed and ashes for the purposes stated.

In order to provide a continuous supply of fuel to the grate, a suitable hopper 97 may be mounted at any convenient location with a chute 98 terminating just above the upper forward end of the grate bottom, and in addition to the lower end of said chute being open, a portion of the rear wall may also have an opening 99 across which is disposed a sliding gate 100 mounted in guideways 101 and by adjusting the height of the lower edge of said gate above the grate, thus regulating the effective size of the opening 99, the depth 65 of the fuel bed can be varied. Coal in the hopper 97 is resting upon the grate 15 and therefore at each intermittent reciprocating movement of the grate the fuel resting thereon will be moved rearward relative to this movement may be one-half inch or it may be two inches or anything else according to the length of movement of the grate, the kind of fuel used, and under some conditions the length of time the grate rests between movements.

70 This step by step movement of the fuel will

finally carry the same over the main part of the grate where combustion takes place and as the bed of fire gradually moves rearward it will be turned into the products of combustion or ashes and said ashes will be forced on and on by the 80 movement of the bed of fire and the new fuel of the rear until said ashes drop off the rear end of the grate.

When a fire is burning each movement of the grate will cause ashes to drop off the rear end thereof, will shift the bed of fire rearwardly and will add new fuel to the zone of combustion so that it will take fire from the preceding burning fuel.

While I have shown and described a pair of 90 impulse springs, cushion springs, and push rods, I desire it understood that one or more of these parts can be employed to accomplish the desired results.

From the foregoing, it is believed that the 95 advantages of the invention in practical use will be appreciated, and they need not therefore be referred to in more detail.

A mechanism for a furnace or boiler constructed in accordance with the invention cannot only 100 be built cheaply and operated economically, but requires very little attention and for reasons which have been explained in full, a wide range of regulation is possible.

Of course I do not wish to be limited to the 105 exact details of construction as herein shown, as these may be varied within the limits of the appended claims without departing from the spirit of my invention.

Having thus fully described my invention, what 110 I claim as new and useful is:—

1. A grate mounted for oscillating movement, a bracket supported adjacent one end of the grate, push rods connected with the grate and passing through a portion of the bracket, springs 115 mounted on said push rods on opposite sides of that portion of the bracket through which said push rods pass for opposed actions, means carried by the push rods engaging the ends of the springs on the inside of the bracket, a cushion 120 plate engaging the springs on the outside of the bracket and through which the push rods pass, means to adjustably connect said cushion plate with the bracket, stops adjustably mounted on the outer ends of the push rods for coaction with the 125 cushion plate, and means to move the grate in a direction for compressing the springs on the inside of the bracket, said means releasing the grate at the end of the movement whereby the springs on the inside of the bracket will move 130 the grate in the opposite direction and said last mentioned movement will be suddenly arrested by contact of the stops with the cushion plate.

2. A grate for oscillating movement, a bracket supported adjacent one end of the grate, push 135 rods connected with the grate and passing through a portion of the bracket, springs mounted on said push rods on opposite sides of that portion of the bracket through which said push rods pass for opposed actions, means carried by the push rods 140 engaging the ends of the springs on the inside of the bracket, a cushion plate engaging the springs on the outside of the bracket and through which the push rods pass, means to adjustably connect said cushion plate with the bracket, stops 145 adjustably mounted on the outer ends of the push rods for coaction with the cushion plate, pedestals carried by the bracket, a notched swinging link pivoted at its upper end to one of said pedestals, a pull bolt connected with said link and the grate, 150

a shaft journalled in the pedestals, a jump cam mounted on said shaft for coaction with the swinging link whereby the latter will be actuated to move the grate by small increments in one direction and finally release the same for movement by the springs in the opposite direction and means to transmit an intermittent motion to said shaft.

3. The structure set forth in claim 2 in combination with a ratchet wheel fixed to said shaft, rings having peripheral enlargements, said rings

being mounted on opposite sides of the ratchet wheel for rotation relative thereto, a rocker arm journalled upon the shaft, means to oscillate said rocker arm and a pawl including a nose for coaction with the ratchet wheel and ears on opposite sides of said nose for coaction with the rings, the positioning of the ring enlargements determining the location where the nose will engage the ratchet wheel.
